UNITED STATES PATENT OFFICE.

MARTIN F. KETTLER, OF HOUSTON, TEXAS, ASSIGNEE TO DOWNING PNEUMATIC WHEEL COMPANY, OF HOUSTON, TEXAS.

RESILIENT WHEEL.

1,140,686.

Specification of Letters Patent. Patented May 25, 1915.

Application filed March 28, 1914. Serial No. 827,971.

To all whom it may concern:

Be it known that I, MARTIN F. KETTLER, citizen of the United States, residing at Houston, in the county of Harris and State 5 of Texas, have invented certain new and useful Improvements in Resilient Wheels, of which the following is a specification.

My invention relates to resilient wheels and particularly to that class of resilient 10 wheel wherein an outer rim section is supported upon a pneumatic cushion disposed between the rim section and a central hub section.

The main object of my invention, generally speaking, is to simplify wheels of this character, cheapen the construction thereof and render them very effective.

A further object is to improve the means whereby the floating ring may be adjusted 20 to thereby adjust the cushion.

A still further object is to improve the construction of the spokes of the spoke section.

Still another object is to so construct the 25 floating ring that the pneumatic cushion therefor may be readily removed and replaced and readily inflated.

Still a further object is to improve the means whereby lubricant may be applied 30 to the contacting faces of the rim section and the hub section of the wheel.

Other objects will appear in the course of the following description.

My invention is illustrated in the accompanying drawings wherein:

Figure 1 is a face view of a wheel constructed in accordance with my invention, the front casing plate being partly broken away. Fig. 2 is a vertical section on the 40 line 2—2 of Fig. 1. Fig. 3 is a face view of the inner casing plate. Fig. 4 is a face view of the outer casing plate. Fig. 5 is a perspective view of the outer ring section of the outer casing plate. Fig. 6 is a perspective view of the removable cone. Fig. 7 is an elevation of one of the bolts used for holding the rim section to the hub section.

Fig. 8 is an enlarged fragmentary section on the same line as Fig. 2. Fig. 9 is a fragmentary perspective view of a portion of the rim, one of the spokes and a portion of the felly together with the outer and inner casing plates. Fig. 10 is a longitudinal sec-

tion through the rim, spoke and felly section to show the method of constructing 55 these parts.

Corresponding and like parts are referred to in the following description and indicated in all the views of the accompanying drawings by the same reference characters. 60

Referring to these drawings, 2 designates an axle carrying at its extremity the head 3. Surrounding this axle 2 is the hub 4 which at its outer end and upon its interior face is provided with the notches 5 which 65 are adapted to engage with teeth on the head 3.

The hub 4 upon its exterior face is formed with screw threads 6 adjacent its outer end, and inward of these screw threads is formed 70 with a cylindrical portion 7 forming a cone seat and then with a conical face 8. Beyond this conical face 8 the hub is formed with the outwardly projecting flange 9, and beyond this flange the outer face of the hub is 75 extended concentric to the inner face as at 10. A cap 11 having interior screw threads is adapted to be engaged with the exterior screw threads of the hub 4 at its outer end. This cap has a flat annular portion 12 between its center and periphery which is of 80 such extent as to project inward beyond the inner face of the hub 5.

Bolted or riveted to the annular flange 9 is the annular plate 13, this plate being 85 slightly dished and formed with a marginal annular flange 14. Also riveted to the flange 9 inward of the plate 13 is a guard or shield 15 annular in form, the periphery of which is inwardly bent as at 16. These plates 13 90 and 15 are permanently fastened upon the hub as is shown plainly in Fig. 2. Opposed to the body of the plate 13 is a removable plate 17 which is also slightly dished and which is adapted to engage with an annular 95 plate 18 which confronts the annular portion 14 of the plate 13. The plate 17 and the annular plate 18 are detachably connected to each other as will hereafter more fully appear.

Disposed upon the seat 7 is a cone 19 which abuts against a shoulder 20 formed at the junction of the flat portion 7 with the inclined portion 8 of the hub, this shoulder limiting the inward movement of the cone 105 19. This cone is formed with a key seat 21

for the reception of a key 22 which engages in a key seat 23 formed in the hub. Thus the cone 19 is held for rotation with the hub. The cone 19 is held to its seat by means of 5 the annular nut 24 which engages the screw threads 6 and is disposed between the butt end of the cone 19 and the inner face of the plate 17. An annular nut 25 also engages the screw threads 6 and bears against the plate 17. This annular nut 25 is held in 10 locked engagement upon the hub by engagement with the cap 11, the cap 11 thus acting as a lock nut to the nut 25.

Disposed around the hub 4 and within the 15 casing formed by the plates 13 and 17 is a ring designated generally 26. This ring is formed in two sections 27 and 28. The section 27 is annular in form and its margin is formed with the inwardly projecting annular flange 29 having a beveled face which 20 bears upon the inclined face 8 of the hub and upon its outside face with the annular inwardly curved clencher flange 30. The opposed section 28 abuts upon its inside edge 25 against the section 27 and is also formed upon its outer margin with the projecting flange 29^a and upon its opposite face with the inwardly curved clencher flange 30^a. The two sections of the floating ring are 30 connected to each other by means of a bolt 31 which is reduced adjacent its inner end and screw threaded as at 32. The main portion of the bolt is smooth upon its outer face and passes loosely through the section 35 28 but has screw threaded engagement with the section 27. As many of these bolts may be used as desired. It will be obvious that by turning these bolts 31 in one direction, the two sections of the floating ring 26 may 40 be drawn toward each other and by turning the bolts in the opposite direction they may be forced apart from each other thus permitting the introduction of a pneumatic tire between the clencher flanges of the sections.

The cushion 33 of my improved tire is made preferably as shown in Fig. 2 in the form of a split pneumatic tire having the clencher flanges 34 adapted to be engaged 50 with the clencher flanges 30 and 30^a. This tire or cushion 33 is preferably composed of a core or body of rubber designated 35 with an interior layer of canvas 36 and an outer layer of canvas 37, these canvas layers being 55 vulcanized into the rubber. Of course, I do not wish to limit myself to any particular form of tire or cushion.

For the purpose of inflating the cushion 33, I provide the air inlet pipe 38 which 60 extends through the section 28 of the floating ring and whose inside end is outwardly bent as at 39 terminating in a head 40. This air inlet pipe 38 is engaged with the tire by means of the head 40 and has screw 65 threaded engagement with annular members

41 embedded in the tire. The outer end of the air inlet pipe is interiorly enlarged and has fitted therein a ball valve 42 and a valve seat against which the valve 42 is designed to rest in order to prevent the escape of air 70 from the cushion. A cap 43 is removably fitted upon the end of the stem of the valve and serves as an additional means for preventing the escape of air.

As illustrated most clearly in Fig. 5, the 75 inner margin of the annular plate 18 is outwardly bent as at 44 and this outwardly bent flange 44 is formed at intervals with the bayonet slots 45. The outer margin of the annular member 17 is inwardly bent or 80 flanged as at 46 and formed at a plurality of points with inwardly projecting studs or pins 47. These are arranged at intervals corresponding to the disposition of the slots 45 so that the studs may be inserted in the 85 slots and then the members 17 given a turn in one direction thus locking the plate or member 17 in its engagement with the annular member 18. The plate 17 is held locked by the nut 25. When it is desired to 90 remove the plate 17 from its engagement with the annular plate 18, the nut 25 is released and the plate 17 is rotated a distance sufficient to disengage the studs 47 from the angular ends of the bayonet slots 95 45 and then the plate is pulled directly outward thus entirely disclosing the interior of the casing formed by the plates 17 and 18.

The rim or spoke portion of the wheel is constructed as illustrated in Fig. 9. It 100 comprises a rim section 48 having extending therefrom spokes 49 which are integrally formed with a felly 50. The rim section 48, the spokes 49 and the felly 50 are all formed integrally of sheet metal. Preferably this 105 rim section 48, the spokes 49 and the felly 50 are formed of two lateral sections or halves, each section being integrally formed of sheet metal and the like two half sections being welded to each other as illustrated 110 clearly in Fig. 10. The opposite faces of the rim section 48 are formed with annular depressions 51 for the reception of lubricant. At the junction of alternate spokes 49, the rim is outwardly extended as at 52 115 and the outer plates of the rim section are formed at this point with an opening 53 within which is disposed a cylindrical sleeve 54 which extends entirely across the rim section thus making a cylindrical chamber 55 120 in alignment with each alternate spoke. The margin 17 of the plate 13 and the plate 18 at intervals corresponding to the alternate spokes are enlarged as at 56 to correspond with the enlarged portions 52 of the rim 48 125 and passing through the chamber 55 and engaged with the marginal portion 14 of the plate 13 and with the annular plate 18 is a bolt 57, the extremities of which are reduced for passage through the portion 14 of plate 130

13 and through the plate 18, these reduced portions being screw threaded for engagement with the nuts 58 and 59.

Surrounding these bolts 50 is a buffer 60 of rubber or other suitable resilient composition. This buffer is adapted to engage with the wall 54 of the chamber 55 in the operation of the wheel. It will be seen that the lateral faces of the rim portion 48 of the 10 rim section have sliding engagement with the inner faces of the plates 14 and 18 and that this rim section therefore has free movement inward or outward relative to the central or hub section. The inner wall 15 51 of the rim section rests upon and bears at all times on the outer face of the cushion 33, this cushion 33 therefore acting to yieldingly and pneumatically support the rim section with its projecting spokes and the 20 felly.

The rim section 48 at points intersected by the axes of the alternate spokes 49^a is formed with oppositely disposed perforations 62 through which pass the sleeves 63 25 which are welded or brazed to the sheet metal of the rim section. These sleeves 62 each forms the wall of a bolt passage 64. The plate 18 upon its outer face opposite each of these passages 64 is formed with 30 an opening 65 formed by an outstanding wall 66 interiorly screw threaded for engagement with a plug 67. When for any cause the pneumatic cushion has become deflated or damaged so that it is not effective 35 and it is desired to use the wheel, lock bolts 68 are adapted to be inserted through the passages 64. Each of these bolts is formed with a smooth portion 69 screw threaded at its outer end as at 70 for engagement with 40 the screw threads of the wall 65. Beyond this screw threaded portion 70 the bolt is formed with the many sided head 71 having the outwardly projecting shoulder 72 disposed between the screw threads 70 and the 45 main portion of the head. This shoulder is adapted to engage against the edge face of the wall 65. The lock bolt projects entirely through the passage 64 and into openings formed in the plate 13. It will be seen that 50 when all these lock bolts are in position, the rim section will be held from movement relative to the hub section of the wheel.

The felly of the wheel as illustrated in Fig. 9, is formed with the laterally disposed 55 inwardly curved flanges 73 which are adapted to engage with the lateral flanges of a resilient tread or tire 74 of any suitable form but preferably formed with the annular side channels 75 crossed by intersecting 60 ribs 76 so as to give a degree of resilience to this rubber tire.

Under ordinary circumstances and in the ordinary use of the wheel, the bolts 68 are of course removed and thus the rim section 65 proper 48, its connected spokes 49 and the

felly 50 are movable bodily inward and outward with relation to the cushion 33. The cushioning cylinders 60 act as shock absorbers and thus should the shock imparted to the wheel be so great as to cause the shock absorbing cushions 60 to engage with the 70 walls 54, the absorbers or cushions will be compressed to a greater or less degree and thus prevent undue compression upon the pneumatic cushion 33, it being understood that greater resistance is offered by the 75 shock absorbing cushion 60 than by the pneumatic cushion 33. Ordinarily, however, where the wheel is not being subjected to very great shocks, the walls 54 of the chambers 55 do not come in contact with the corresponding shock absorbing cushion 60 and they have no effect. It is only when the wheel is subjected to very great strain or jar that the shock absorbers come into action. Where as before stated the pneumatic cushion becomes deflated for any reason, is ruptured or otherwise prevented from 80 proper action, the bolts 68 may be inserted through the passages 64 and thus the rim section connected rigidly with the hub section. 85

If it is desired to replace the pneumatic cushion 33, the cap 11 is removed as is the nut 25. The plate 17 is then rotated slightly 90 until its studs disengage from the slots 45 and then the plate is withdrawn after which the nut 24 is unscrewed, both the nuts 24 and 25 being provided with means for the engagement of a spanner wrench. When these nuts have been removed, the cone 19 may be withdrawn and the bolts 31 removed thus forcing the sections 27 and 28 of the floating ring 26 apart thus disengaging the floating ring from the cushion 33 and permitting the cushion to be withdrawn and a new cushion inserted. If the cushion becomes deflated it is only necessary to remove the cap 11, the nut 25 and the plate 17, whereupon access may be had to the inflation pipe 38 and this pipe readily connected to any ordinary means for tire inflation. When the nut 24 is turned up to its full extent it will hold the removable cone 19 against the shoulder 20 and thus force the floating ring 26 outward and force the cushion 33 firmly against the inner end wall 61 of the rim section. 100

The advantages of my improved construction lie in the simplicity of its construction, ease with which the parts may be assembled and disassembled, and the ease with which access may be had to the cushion 33. The plates 13 and 17 being of sheet metal may be readily stamped out, as may the annular plate 18, and this is also true of the two sections or plates from which the complete rim, spokes and felly are formed. 110

As will be seen from Fig. 9, the channels 51 for the reception of lubricant are dis- 120 125 130

posed between and separated from the openings or passages 55 and 64 by the walls 51. Thus these recesses or channels 51 may be filled with grease or other lubricant or with felt or wicking which may absorb lubricant and be a constant feeder for lubricating the flanges. This wicking or other filling material will prevent the lubricant leaking out. The material contained within these channels will, of course, lubricate the contacting faces of the plates 18 and 13 with the rim section. As will be seen clearly from Fig. 9, I secure great strength and at the same time lightness by constructing the wheel, and particularly the rim portion thereof, from sheet metal sections welded together and having the form illustrated. The rim section proper 48 is hollow and is strengthened by bending the metal to form the channels 51. The spokes are also hollow as is the felly. Inasmuch as the sections of the rim are welded together, I form practically an integral rim, the joint formed by the welding of the two sections together being as strong as the main body of the sections. As illustrated in Fig. 10, the lateral plates forming the rim section are overlapped thus forming a very strong joint.

It will further be seen in this connection that the rim proper is braced by the transversely extending sleeves 63 and 54, these sleeves thus serving two functions, namely, strengthening the hollow rim section and forming the walls of the passages 55 and 64. It will further be noted particularly from Fig. 8 that the bolts 57 are so formed as to provide shoulders against which the ring plate 18 and the marginal flange 14 of plate 13 bear, thus preventing any inward movement of these plates which would tend to create too great a friction between these plates and the rim section proper 48. One of my objects in this construction is to so form the several parts that no binding action will occur to prevent the free movement of the rim section relative to the hub section and the casing and yet support this rim section against lateral deflection.

What I claim is:

1. In a wheel of the character described, a hub screw threaded upon one end, a pneumatic cushion surrounding the hub, an in-

ner casing plate having an annular margin, an outer casing plate slidably removably fitted upon said hub, a nut holding said outer casing plate in place, a ring plate disposed opposite the annular margin of the inner casing plate, a rim section including a rim proper disposed between the confronting faces of the margin of the inner casing plate and the ring plate, the inner edge of the ring plate being formed with an outstanding flange provided with bayonet slots, the outer casing plate having an inwardly turned flange fitting over the outstanding flange of the ring plate and provided with studs engageable in said slots.

2. In a wheel of the character described, a hub, a cushioning member supported upon the hub, outer and inner casing plates supported upon the hub and housing the cushioning member, and a rim section supported between the casing plates and upon the cushioning member, said section comprising a hollow rim proper, hollow spokes and a hollow felly, the rim section being formed of lateral halves connected to each other, and transversely extending sleeves disposed at intervals through the rim proper and bracing the sides of the rim.

3. In a wheel of the character described, a hub, a cushioning member supported upon the hub, outer and inner casing plates supported upon the hub and housing the cushioning member and a rim section supported between the casing plates and upon the cushioning member, said section comprising a hollow rim proper, hollow spokes and a hollow felly, the rim section being formed of lateral halves connected to each other, and transversely extending sleeves disposed at intervals through the rim proper and bracing the sides of the rim, the side walls of the rim section being formed with longitudinally extending grooves whereby to further strengthen the side walls of the rim section.

In testimony whereof I affix my signature in presence of two witnesses.

MARTIN F. KETTLER. [L. S.]
